UNITED STATES PATENT OFFICE.

ROBERT NEIL WILLIAMS, OF LONDON, ENGLAND, ASSIGNOR TO POWERS ACCOUNTING MACHINE COMPANY, OF NEW YORK, N. Y., A CORPORATION OF DELAWARE.

TABULATING-MACHINE AND CARDS THEREFOR.

1,274,484.

Specification of Letters Patent. Patented Aug. 6, 1918.

Application filed November 13, 1915. Serial No. 61,259.

To all whom it may concern:

Be it known that I, ROBERT NEIL WILLIAMS, a citizen of the United States of America, residing in London, England, have invented certain new and useful Improvements in Tabulating-Machines and in Cards Therefor, of which the following is a specification.

This invention relates to improvements in 10 and relating to tabulating machines of the type in which a card is employed having perforations representing various monetary or other values or quantities, and which perforations control counting and printing 15 mechanism whereby the said values or quantities are ascertained and translated into printed figures and impressed upon a paper or other sheet or band.

The present invention has for its object 20 to provide means whereby certain perforations in the cards which represent the letters of the alphabet may be translated into any desired group of letters, the name of an individual for example, and translated into 25 printed characters.

In the cards commonly employed for the machines under consideration there are provided a number of fields each representing the various data of which the particulars 30 are to be ascertained. According to the present invention a field is provided designed to represent the letters of the alphabet, and which field is capable of accommodating a number of columns of perforations 35 so as to provide for a number of letters comprising, for example, a name.

In order that the invention may be the better understood drawings are appended in which:—

40 Figure 1 is a plan of a card embodying the present invention.

Fig. 2 is a side view of mechanism designed to coöperate with said card.

Fig. 3 is a sectional view showing the 45 cards in position in the machine and their relation to the stop pins for the sectors.

Referring to the accompanying drawings, *a* represents the ordinary card which is of standard size, and which card is divided into 50 the desired number of fields *b* representing various data of which particulars are to be ascertained. *c* indicates a field distinct from the fields already referred to, and in which a column of perforations may be formed, each 55 of such perforations representing a letter of

the alphabet. I prefer to employ what may be termed a standard column, in which there can be eleven perforations, the presence of a perforation in any one of nine positions representing one of three letters of the alphabet. The remaining perforations above referred to indicate which particular letter of the three is intended. As an illustration, starting from the top of the column, perforations in the various positions in the column represent successively the letters:—

A	J	S	70
B	K	T	
C	L	U	
D	M	V	
E	N	W	
F	Q	X	
G	P	Y	
H	Q	Z	75
I	R	—	
2nd			
3rd			

the last of the column being utilized to represent a blank or hyphen.

In the illustration for the sake of clearness the full number of perforations are shown, each being identified by the letters it may represent. Supposing it is desired to produce the name of an individual, Smith 85 for example, then such perforations would be formed at points in each column as would represent the particular letters S, M, I, T, H, for example a hole on the line AJS plus a hole at 3 in the first column, a hole on the line DMV plus a hole at 2 in second column, a hole at IR—, without any further perforation in 3rd column, and so on. This arrangement of letters is purely arbitrary and any other arrangement may be adopted. 95

By arranging the perforations in the manner described it is possible to employ the standard cards now in use upon machines also of standard construction.

While the application of the invention is 100 not limited to any particular type of machine, it may conveniently be applied to machines such as form the subject of British Letters Patent No. 26896 of 1913, in which case there is provided a drum 1 arranged in axial alinement with the roller 2 over which the paper *a* passes upon which the items are recorded. The drum 1 is spring driven in one direction by means of a spiral spring 3 disposed therein, and it is so mounted as 110

to be capable of a certain motion transversely of the line of its center of rotation. The periphery of the drum 1 is provided with type 4, a hammer 5 being provided 5 which in striking the drum causes it to move forward and impress the paper α . The hammer may carry a pawl 7 which, engaging suitably shaped teeth 8 upon a ratchet wheel 9 upon the drum 1, will assist in positioning said drum should it have moved 10 slightly beyond the desired limit. Coiled around a sheave 10 upon the type drum is a flexible body such for instance as a steel or other substantially inextensible wire 11, 15 and which wire 11 at its opposite end is attached to a spring controlled swinging member 13 mounted and actuated in the same manner as the tabulating actions of the aforesaid machine, and which member 13 20 has three projections 14, 15, 16, upon its periphery, 12 indicates a sector by means of which, as will presently be explained, additional movement may be permitted to the swinging member 13. The sector 12 is 25 provided with a single projection or stop 17 and in addition thereto it has secured to it two bell crank levers 18, 19, one arm 18^a 19^a of each of said levers being provided with a tooth 18^c 19^c adapted to engage projections 14 15 upon the swinging member. The levers 18 19 are disposed so that one 30 end will engage one of the control pins 21, positioned in the manner described in the specification of the aforesaid Letters Patent 35 No. 26896 of 1913, when such pin 21 is raised and the levers are coupled together so that while the first, 18, may be operated alone, the second, 19, cannot be operated without actuating the first. When the second lever 40 19 is actuated the movement of the member 13 is limited by the third stop 16 thereon which comes into contact with projection 20 on the face of the member 12.

As shown in Fig. 3 the card indicated by 45 w' is fed by rollers not shown, between perforated plates m m' with which coat several series of pins such as those 21. The lower ends of the pins 21 are provided with heads n supported in recesses o in the upper 50 perforated plate m . Arranged beneath the lower perforated plate m' is a pin box o' vertically reciprocated by means of a roller and cam as described in the aforementioned British Patent. The pin box o' carries several series of pins such as o^2 the said pins being urged upward by means of the springs o^3 by which they are encircled, the upward movement of each of said pins o^2 being limited by means of a collar p . The 55 rise of the pin box allows any pins o^2 in register with holes in the card to raise the corresponding pin 21 which remains protruding from the bottom of the pin box against the action of the spring o^3 . When 60 the box descends the pins o^2 under the ac-

tion of their spring are withdrawn and the card is ejected, the parts then being returned to their initial position.

The card previously provided with the desired perforations in the various fields is 70 passed through the machine, and while the tabulating mechanism of the main machine is being set, the perforations in the name field will cause an appropriate setting of the control pins of each of the sectors 12. 75 One sector is provided for each column upon the field together with a set of control pins 21. By this means each of the type wheels or drums will receive a corresponding setting so that when the printing of the values 80 represented by the perforations in the main field is effected there will simultaneously be printed the name of the individual concerned. The operation of the sector 12, swinging member 13, hammer 5, is effected 85 in the same manner and by similar means to the corresponding members of the main machine. A suitable ribbon w is provided for the type.

I claim:

1. In a machine for tabulating statistical and other data, mechanism controlled by a perforated card whereby certain perforations in said card may be indicated as letters of the alphabet, said mechanism comprising a type wheel having a complete alphabet thereon, a row of pins for controlling the type wheel, the pins being adapted to coöperate in combinations; and means for positioning said type wheel according to the 95 combination of the controlling pins.

2. In a machine for tabulating statistical and other data, mechanism controlled by a perforated card whereby certain combinations of perforations in said card may be indicated as a word, said mechanism comprising a type wheel having a complete alphabet thereon, a row of pins for controlling the type wheel, the number of controlling pins being less than the number of letters in the 100 alphabet on the type wheel, the pins being adapted to coöperate in combinations; and means for positioning said type wheel according to the combinations of controlling pins.

3. In a machine for tabulating statistical and other data, mechanism controlled by a perforated card whereby perforations arranged in a single column in said card may be indicated as letters of the alphabet, the 110 number of perforations in a row being less than the number of letters in the alphabet, the perforations forming combinations with one another to indicate all of the letters of the alphabet.

4. In a machine for tabulating statistical and other data, the combination of a character carrying part provided with a plurality of different characters; a group of control pins adapted to control said part in 115 120 125 130

combinations; and means for positioning said character carrying part according to the combination of the control pins.

5. In a machine for tabulating statistical and other data, the combination of a character carrying part provided with a plurality of different characters; a group of control pins adapted to control said part in combinations, the number of pins in said group 10 being less than the number of characters on said part; and means for positioning said character carrying part according to the combination of the control pins.

6. In a machine for tabulating statistical 15 and other data, the combination of a group of pins adapted to be controlled by perforated cards; a pair of relatively movable members both movable relative to said group of pins, certain of the pins being adapted 20 to stop one of the members; a type carrying part operatively connected to the other pin; and means controlled by said pins for causing relative movement between said members.

25 7. In a machine for tabulating statistical and other data, the combination of a group of pins adapted to be controlled by perforated cards; a movable member and a movable part adapted to move relatively to 30 said pins and each other; a spring operated character carrying part operatively connected to said movable part; and means controlled by certain of said pins to permit and prevent limited relative movement be- 35 tween said movable part and member, said

member being adapted to be controlled in its movement by other of the pins.

8. In a machine for tabulating statistical and other data in which a swinging sector is employed controlled by pins the operation 40 of which pins is in turn controlled by means of perforated cards, a spring controlled drum, type upon said drum, a sheave upon the spindle of said drum, a flexible body wound upon said sheave and connected to 45 the sector, whereby the type bearing drum may be positioned by means of perforations in the card.

9. In a machine for tabulating statistical and other data in which a swinging sector 50 is employed controlled by pins the operation of which pins is in turn controlled by means of perforated cards, a spring controlled drum, type upon said drum, a sheave upon the spindle of said drum, a flexible body 55 wound upon said sheave and connected to the sector, a second sector, levers upon said sector, stops upon the first sector engaging said levers, stops operated by pins which in turn are operated by perforations in the 60 card and whereby the position of the sector controlling the type drum is regulated.

In witness whereof I have hereunto set my hand in the presence of the two undersigned witnesses.

ROBERT NEIL WILLIAMS.
